UNITED STATES PATENT OFFICE.

WILLIAM E. BAILEY, OF BEVERLY, MASSACHUSETTS, ASSIGNOR TO ARBETTER
FELLING MACHINE COMPANY, OF BOSTON, MASSACHUSETTS, A CORPORATION
OF MAINE.

BLINDSTITCH SEWING-MACHINE.

1,091,619.

Specification of Letters Patent. Patented Mar. 31, 1914.

Application filed December 22, 1908. Serial No. 468,849.

To all whom it may concern:

Be it known that I, WILLIAM E. BAILEY, a citizen of the United States, and a resident of Beverly, in the county of Essex and State 5 of Massachusetts, have invented an Improvement in Blindstitch Sewing-Machines, of which the following description, in connection with the accompanying drawing, is a specification, like letters on the drawing 10 representing like parts.

This invention relates to a blindstitch sewing machine for operating upon the work which by reason of its shape cannot be spread out flat upon the ordinary work-support, such for example as the sleeve and 15 leg portions of garments.

The stitch-forming instrumentalities and various other features of the machine are 20 preferably of the type of construction similar to that of the well-known Arbetter machine.

While various blindstitching operations may be performed with the machine embodying this invention it is particularly 25 intended for felling work upon sleeves and trousers legs. It is desirable for simplicity and economy of construction, as well as for ease of handling and operation, that the stitching and feeding mechanisms should 30 always operate in the same direction. The classes of work, however, to be operated upon require the positioning of the seam in reverse directions with respect to the edge of the article. For example, in felling the 35 bottoms of the legs of trousers the fabric is usually unlined, and this fabric is turned in and felled directly to itself; while in felling the ends of sleeves the fabric is usually lined and the inturned edge of the lining felled to the inturned fabric. Regarding 40 the edge or end of the trousers or of the sleeve respectively it will be recognized that the felling stitch must be made in the opposite direction in the one case to that in the 45 other.

The present invention provides a cylindrical work-support adapted to enter the article to be stitched, such as the sleeve or trousers leg, and allow the article to be fed 50 without obstruction around this support. This support is carried by a standard yieldingly mounted so that the work will be held yieldingly against the stationary presser-foot, and the cylindrical work-support projects horizontally to the right or the left of

the standard according to the nature of the work to be performed, as in the case of felling the bottoms of trousers legs or the sleeve ends.

The invention also involves a yielding 60 work-plate section in the cylindrical support beneath the presser-foot, the tension of which may be varied as desired.

The invention also involves the use of a feeding mechanism mounted and operating 65 entirely above the cylindrical work-support.

The invention also involves a bender so constructed and located as not to interfere with the passage of the work around the cylindrical work-support. 70

The invention will more fully appear from the accompanying description and drawings and will be particularly pointed out in the claims.

The drawings illustrate a preferred form 75 of construction embodying the invention, in which the stitch-forming mechanism and various other features, many of which it is unnecessary to illustrate, are the same as those characterizing the Arbetter type of 80 machine above referred to.

In the construction illustrated the machine is designed for use upon work of the character of the bottoms of trousers legs, where the work must be presented from the 85 right-hand side of the machine, or in other words, slid over a cylindrical support pointing to the right in order to have the operation of the stitch-forming and feeding mechanisms occur in the same direction as is 90 customary in ordinary work.

In the drawings, Figure 1 is a front end elevation of the machine. Fig. 2 is a side elevation of the forward portion of the machine, partially in cross-section and with 95 some of the parts removed. Fig. 3 is a rear elevation of the feeding mechanism and its supporting and operating parts. Fig. 4 is a top plan view of the presser-foot.

In its general arrangement the machine 100 herein illustrated comprises a work supporting base or bed and an overhanging head A², only the forward portions of which are illustrated. The overhanging head A² supports and carries the entire stitch-forming 105 mechanism and the stationary presser-foot, as in the case of the Arbetter type of machine. In the machine illustrated the overhanging head carries also the entire feeding mechanism so that the stitch-forming mech- 110

anism, the feeding mechanism, and the presser-foot, are located upon one and the same side of the work, viz., above the work-support.

5 The stitch-forming mechanism itself is fully illustrated in the before-mentioned patents and comprises as therein described the curved needle a^2 mounted in the needle-carrying arm b' , carried in turn by the 10 needle-carrying rock-shaft B^7 , in turn mounted in a transverse bearing carried by the vertical rock-shaft B^{10} , to which the rocking motion is imparted at the proper times, as set forth in said patents, to cause 15 the needle to move at one time parallel with, and at another time diagonal to, the feed. This movement of the needle in felling work enables one stitch to be taken into the main or base fabric close up to and parallel with 20 the edge to be felled thereto, and another stitch to be taken diagonal into the overlying layer at the edge.

The main driving shaft of the machine is indicated at B and carries at its forward 25 end the disk B^2 from which, by means of a connecting rod B^3 to the crank-arm B^4 of the needle-carrying rock-shaft B^7 the proper oscillatory movements are imparted to the needle. The mechanism for rocking the 30 needle bodily to cause it to move first in the straight and then in the diagonal path with respect to the edge are not illustrated and need not here be described.

The complementary stitch-forming mechanism is indicated as a revolving hook C , inclosing a bobbin case and bobbin C^2 , and carried by a support C^3 depending from the overhanging head A^2 . The rotary hook is supported and driven by suitable connections, not necessary to illustrate or describe, 40 from the main driving shaft and moves in a plane transverse and oblique to the paths of the needle.

The presser-foot D is similar to that 45 shown in the above-mentioned patents and is rigidly supported from the overhanging head A^2 . It is shown as provided with an opening D^2 constituting the needle throat, and as having its heel portion concaved on 50 the upper surface at D^3 to provide for the movement of the needle in making the straight and diagonal stitches. It is also shown as provided with parallel openings D^4, D^5 , one at each side of the needle throat 55 and the point at which the stitch is taken, these openings allowing for the movement of the feed dog to be described. It is also provided with a suitable guard D^6 , with an edge-gage D^7 , and a finger D^8 for raising 60 the edge of the overlying layer.

The feeding mechanism, which as stated is mounted in the overhanging head A^2 , comprises a suitably constructed feed dog E , and means for giving it an up and down and 65 forward and backward movement. In the

form of mechanism illustrated a member E^2 is mounted to slide vertically in the head A^2 , this sliding movement being secured by a cam E^3 carried by the shaft B and engaging ribs E^4 projecting from the member E^2 . 70 This sliding member E^2 carries an elongated transverse bearing E^5 in which is fulcrumed a bell-crank lever E^6 . The feed dog E is fastened to the depending arm E^7 of the bell-crank lever by set-screws E^8 , while the 75 other arm, E^9 , which is rotarily adjustable with respect to the arm E^7 by means of the set-screw E^{10} , projects upwardly and is held against the face of a second cam E^{12} on the main shaft B by means of a spring E^{13} . The extent of the swinging movement of the bell-crank lever and consequently the extent of the backward and forward movement of the feed dog is determined by means of a set-screw E^{14} mounted on the sliding member E^2 . 80

The feed dog may be constructed according to requirements of the particular work, but is herein shown as provided with two serrated, longitudinally-extending projections E^{15} and E^{16} , working through the slots 90 D^5 and D^4 respectively in the presser-foot so as to grip and feed the fabric at both sides of the point at which the stitch is taken into the fabric, thus securing the positive control of the fabric at all times. A vertical standard F is mounted to slide in ways in the base or bed A of the machine, and is held in place by means of the plate F^2 . This standard F is held yielding upward by a spring F^3 and is depressed when desired by 100 means of the lever F^4 connected to the stud F^5 . The standard F is bent to one side or as illustrated to the left at its upper end, and carries projecting therefrom beneath the stitch-forming mechanism and presser-foot, 105 or as in the case illustrated projecting to the right, a horizontal, cylindrical work-support G . The work-support is of such a size as to allow the tubular work to be operated upon, such for example as a sleeve or trousers leg to be slipped thereover and fed therearound by the feeding mechanism.

The cylindrical work-support comprises a hollow shell closed at the end by a plate G^2 . The cylindrical work-support is also preferably provided with a yielding work plate section directly beneath the presser-foot, and which acts to hold the work in yielding engagement with the presser-foot and feed dog. This yielding work-plate section takes 115 care of the usual inequalities of the work, while the entire work-support and standard yield under extraordinary circumstances and are depressed when the work is to be inserted and removed. The work-plate section H 120 is carried by a post H^2 , slidably mounted in a guideway formed in a vertical projection H^3 from the bottom of the cylindrical support. A set-screw H^4 projecting into a slot 125 in the post H^2 limits the upward movement 130

of the work-plate section. The work-plate section is held yieldingly upward by an arm H^5 journaled on a stud H^6 , a coiled spring H^7 connected at one end to the stud and at 5 the other to the arm acting normally to elevate the arm. The stud H^6 may be rotated and locked in place by the nut H^8 , thus varying the tension of the spring H^7 and consequently the pressure of the work-plate section H upwardly against the presser-foot and feed-dog. It will thus be seen that the "work-supporting base" or bed A supports the main body of the work, while the "cylindrical work support", or "auxiliary work 15 support" as it may be termed, supports that portion of the work in the vicinity of the line of seam so that it may be readily handled and presented to the stitching mechanism, while the "yielding work plate section" supports that portion of the work directly at the stitching point.

The bender point K operates through the work-plate section H and the throat of the presser-foot to project the work into the 25 path of the needle at the required times as usual. In order to secure the operation of the bender without interfering with the passage of the work around the cylindrical work-support the bender point K is carried 30 by a shank K^2 offset at its ends and guided in its central portion in the upper end of the standard F. A plate K^3 is removably secured to the standard at the upper portion to enable the removal and replacement of 35 the bender shank K^2 . The shank K^2 is held yieldingly downward by means of the spring K^4 attached to the bender bar K^5 . The bender bar K^5 slides vertically in bearings K^6 in the plate F², and is given its vertical 40 movement by means of the crank arm K⁷ operated in the usual manner from a cam K⁸. The bender bar K⁵ when elevated comes in contact with the bender shank K² and elevates the bender to project the fabric into 45 the path of the needle. On the depression of the bender bar the bender moves to inactive position under the influence of the spring K⁴.

Having described my invention, what I 50 claim as new and desire to secure by Letters Patent, is:

1. A blindstitch sewing machine comprising a work-supporting base, an overhanging head, a presser-foot mounted in 55 said head, an auxiliary horizontal, cylindrical work-support yieldingly and vertically movable with respect to said base, and a yielding work-plate section mounted in said cylindrical work-support beneath said presser-foot, feeding mechanism supported from the overhanging head above and co-operating with said yielding section.

2. A blindstitch sewing machine comprising a work-supporting base, an overhanging 60 head, a presser-foot mounted in said head,

a standard vertically movable with respect to said base, an auxiliary horizontal, cylindrical work-support projecting from said standard beneath said presser-foot, and a yielding work-plate section mounted in said cylindrical work-support beneath said presser-foot, feeding mechanism supported from the overhanging head above and co-operating with said yielding section.

3. A blindstitch sewing machine comprising a work-supporting base, an overhanging head, a presser-foot mounted in said head, an auxiliary horizontal, cylindrical work-support yieldingly and vertically movable with respect to said base, a yielding work-plate section mounted in said cylindrical work-support beneath said presser-foot, feeding mechanism supported from the overhanging head above and co-operating with said yielding section, and means for varying 75 the yielding action of said work-plate section against the presser-foot and feeding mechanism.

4. A blindstitch sewing machine comprising a work-supporting base, an overhanging head, a presser-foot mounted in said head, an auxiliary horizontal, cylindrical work-support yieldingly and vertically movable with respect to said base, a work-plate section mounted in said cylindrical work-support beneath said presser-foot, feeding mechanism supported from the overhanging head above and co-operating with said work-plate section, a stud mounted in said cylindrical work-support, an arm engaging said work-plate section, a spring coiled about 90 said stud and engaging said arm and acting therethrough to hold the work-plate section 95 normally and yieldingly elevated.

5. A blindstitch sewing machine comprising a work supporting base upon which the body of the work may rest and be supported, an overhanging head, a presser foot mounted in said head, an auxiliary cylindrical work-support vertically movable with respect to said base and projecting horizontally between said base and presser foot to allow tubular work to be slipped thereover and fed therearound, and a yielding work plate section mounted in said auxiliary 100 work-support beneath said presser-foot to support the work yieldingly immediately at the stitching point.

6. A blindstitch sewing machine comprising a work supporting base upon which the body of the work may rest and be supported, an overhanging head, a presser foot mounted in said head, a standard vertically movable with respect to said base, an auxiliary cylindrical work-support projecting 120 horizontally from said standard between said base and presser foot to allow tubular work to be slipped thereover and therearound, and a yielding work plate section mounted in said auxiliary work-support 125 be- 130

neath said presser foot to support the work yieldingly immediately at the stitching point.

7. A blind stitch sewing machine comprising feed mechanism, a head, a presser foot mounted in said head, a horizontal cylindrical work support beneath said head, and a yielding work plate section mounted in said cylindrical work support beneath and coöperating with said presser foot.

8. A blind stitch sewing machine comprising a head, a presser foot mounted in said head, a horizontal cylindrical work support beneath said head, a yielding work plate section mounted in said cylindrical work support beneath and coöperating with said presser foot, and feeding mechanism supported from the said head above and coöperating with said yielding section.

9. A blind stitch sewing machine comprising a head, a presser foot mounted in said head, a horizontal cylindrical work support beneath said head, a yielding work plate section provided with a bender opening mounted in said cylindrical work support beneath and coöperating with said presser foot, a bender and means for reciprocating it as required through said opening.

10. A blind stitch sewing machine comprising a work supporting base upon which the body of the work may rest and be supported, an overhanging head, a presser foot mounted in said head, an auxiliary cylindrical work support projecting horizontally between said base and presser foot to allow tubular work to be slipped thereover and fed therearound, a bender projecting through the upper surface of the cylindrical work support adjacent the presser foot and having an offset shank to prevent interference with the work, a reciprocating bender bar and a spring acting to draw the bender shank against the bender bar.

11. A blind stitch sewing machine comprising a vertically reciprocating bender bar, a vertically reciprocable bender having an offset shank to allow for the passage of the work, and a spring acting to draw the bender shank against the bender bar.

In testimony whereof, I have signed my name to this specification, in the presence of two subscribing witnesses.

WILLIAM E. BAILEY.
